UNITED STATES PATENT OFFICE.

JOHAN M. ANDERSEN, OF BOSTON, MASSACHUSETTS, ASSIGNOR OF ONE-HALF TO ALBERT ANDERSON, OF SAME PLACE.

ELECTRIC SWITCH.

SPECIFICATION forming part of Letters Patent No. 638,687, dated December 12, 1899.

Application filed December 23, 1897. Serial No. 683,112. (No model.)

To all whom it may concern:

Be it known that I, JOHAN M. ANDERSEN, a citizen of the United States, residing in Boston, in the county of Suffolk and State of Massachusetts, have invented an Improvement in Electric Switches, of which the following description, in connection with the accompanying drawings, is a specification, like letters and figures on the drawings representing like parts.

This invention relates to an electric switch or circuit-controller and is herein shown as embodied in a switch of that class known as a "double-throw quick-break" switch. In accordance with this invention the double-throw switch is provided with a spring-actuated movable member which is eccentrically mounted so as to be turned preferably through an arc of substantially one hundred and eighty degrees and make contact with coöperating stationary members set at substantially the same distance on opposite sides of the center on which the eccentric turns, so that the movable member may be positively engaged with its coöperating member on opposite sides of the center and may be disengaged therefrom with a quick movement, whereby the switch is rendered equally effective when the movable member coöperates with one stationary member as with the other. These and other features of this invention will be pointed out in the claims at the end of this specification.

Figure 1 is a side elevation of a switch embodying this invention; Fig. 2, a top or plan view of the switch shown in Fig. 1; Fig. 3, a longitudinal section on the line 3 3, Fig. 2; Fig. 4, a side elevation with parts broken away of the switch, showing the same in the act of opening; Fig. 5, a section similar to Fig. 3 with the movable member in the opposite position; Fig. 6, a sectional detail, on an enlarged scale, taken on the line 6 6, Fig. 1, looking toward the right; and Fig. 7, a section on the line 7 7, Fig. 1.

The operative parts of the switch herein shown as embodying this invention are suitably secured to a base A, of suitable insulating material, which in the present instance has fastened to it two sets A' A² of stationary terminals or contact members, each compris-

ing three pairs of metal fingers a² a³ a⁴, which may be fastened into slots in a terminal plate a⁵ by a pin a⁶ or in any other suitable manner, the said plate, as shown, having a post or shank a⁷ extended through the base A and provided with screw-threads a⁸, to be engaged by a lock-nut a⁹. The sets A' A² of stationary terminals are secured to the base on opposite sides of a center shaft or pivot a¹⁰, preferably supported, as herein shown, (see Fig. 7,) by three pairs of uprights a¹² a¹³ a¹⁴, secured to a plate a¹⁵, as by a pin a¹⁶. The metal fingers a² a³ a⁴ and uprights a¹² a¹³ a¹⁴ may and in practice preferably will be secured in place by solder.

The pivot or shaft a¹⁰ has mounted on it, as will be described, the movable member of the switch, which in the present instance comprises an eccentrically-mounted blade or arm b² and a carrier for said blade, which carrier may and preferably will consist of two concentrically-mounted arms or blades b b'. The concentric blades, as shown, are mounted directly upon the pivot pin or shaft a¹⁰, between the uprights a¹² a¹⁴, respectively, while the blade or arm b² is mounted to turn on an eccentric hub b³ on the shaft or pivot a¹⁰. The eccentric hub b³ is loose on the pivot or shaft a¹⁰, but is held stationary, as shown, by means of substantially diametrically opposite lugs b⁵, extended into vertical slots b⁶ in the uprights a¹³. The plate a¹⁵ is provided with a post a⁷⁰, extended through the base A and secured thereto by a nut a⁹⁰.

The carrier or concentric blades b b' are made of sufficient length to project beyond the sets A' A² of stationary contact members and are united at their free ends by a tie-bar b⁷, to which is secured a suitable handle b⁸. The eccentric blade b² is located between the concentric blades b b' and is preferably made shorter than the same and is connected to the concentric blades, as will be described, in such manner as to enable the concentric blades to be moved independent of it, so that an increasing force may be applied to the eccentric blade to remove it from engagement with its coöperating stationary terminals. The increasing force referred to is obtained, as herein shown, by means of a yielding medium, shown as springs b¹⁰ b¹², connected to

the opposite ends of two bars or rods $b^{13} b^{14}$, located above and below the concentric blades $b b'$, and, as shown, normally seated in suitable recesses $b^{15} b^{16}$ in the top and bottom 5 edges or sides of said concentric blades. The bars or rods $b^{13} b^{14}$ are also adapted to engage one of two similar recesses $b^{17} b^{18}$ in the upper and lower edges or sides of the eccentric blade b^2 . (See Figs. 3 and 5.) The concentric blades $b b'$ are adapted to have a certain movement away from their coöperating stationary terminals, without moving the eccentric blade and to then be positively connected to said eccentric blade, so that further 10 movement of the concentric blades will effect a partial disengagement of said eccentric blade from its coöperating stationary terminal and sufficient to permit the springs $b^{10} b^{12}$ to complete said disengagement. The positive 15 connection between the concentric blades $b b'$ and the eccentric blade b^2 may be effected, as herein shown, by means of a cross bar or rod c , secured, in the present instance at its opposite ends, to the concentric blades $b b'$ 20 and extended through one of two slots $c' c^2$ in the eccentric blade. The slots $c' c^2$ are made in the arcs of circles of substantially the same radius, but struck from different centers, and the said curved slots extend in substantially 25 opposite directions from substantially a line through the center of the pivot or shaft a^{10} and extended longitudinally through the eccentric blade b^2 , each of the said slots being carried beyond said longitudinal line a distance 30 substantially equal to one-half the thickness or diameter of the rod or bar c , so as to permit of longitudinal movement of the eccentric blade when turned on its eccentric b^3 to permit one and then the other of the 35 slots $c' c^2$ to be engaged with the bar or rod c .

When the movable member of the switch is in contact with the set A' of stationary terminals, the bar c extends through the slot c^2 , and in the closed position of the switch 40 the said bar bears against the end wall 2 of said slot, as shown in Fig. 3. If now it is desired to open the circuit between the set A' of the terminals and the terminal uprights carrying the pivot a^{10} , the operator moves the handle 45 b^8 in the direction indicated by the arrow 20 in Fig. 4, thereby turning the concentric blades $b b'$ on the pivot a^{10} and manually removing the said concentric blades from engagement with their coöperating terminals $a^2 a^4$. When the blades $b b'$ are disengaged 50 from their coöperating terminals $a^2 a^4$, as described, the eccentric blade b^2 remains in frictional engagement with its coöperating terminals a^3 . Consequently as the concentric 55 blades $b b'$ are turned on their pivot the springs $b^{10} b^{12}$ are placed under tension, being extended, as indicated in Fig. 4, until the bar c , carried by the blades $b b'$, engages the end wall 3 of the curved slot c^2 , and thereaf- 60 ter on the further movement of the concentric blades in the direction of the arrow 20 the eccentric blade b^2 is moved with the blades

$b b'$ until the friction between the blade b^2 and its terminals is overcome by the springs $b^{10} b^{12}$, which completes the removal of the 70 blade b^2 from engagement with its terminals and restores the said blade into its normal position relatively to the carrier or blades $b b'$ substantially in an instant, thereby effecting a sharp quick break in the circuit, and consequently avoiding the formation of arcs. The movement of the blade b^2 by the springs $b^{10} b^{12}$ is arrested by the end wall 2 engaging the bar c . 75

If it is desired to complete the circuit between the movable blade b^2 and the set A^2 of terminals, the handle b^8 is continued on its movement in the direction indicated by the arrow 20 until the said blade is engaged with the terminals A^2 . During the movement just 80 referred to the blades $b b'$ turn on their pivot or center a^{10} , while the blade b^2 turns on the eccentric b^3 , which is shaped so as to move the blade b^2 longitudinally, and thereby remove the slot c^2 from in line with the bar c 85 and bring the slot c' in line therewith and into engagement with the end wall 4 of the said slot, so that as the blades $b b'$ are moved from a central position down toward the set A^2 of terminals the bar c will move the blade b^2 and 90 positively force it into engagement with its coöperating terminals of the set A^2 and into the position shown in Fig. 5. As the blade b^2 is moved longitudinally by its eccentric the 95 rods or bars $b^{13} b^{14}$ are disengaged from one 100 set of recesses b^{17} and engaged with a second set b^{18} . When the handle b^8 is moved from the position shown in Fig. 5 to that shown in Fig. 3 to open the circuit between the terminals A^2 and the uprights in which the blades 105 are pivotally supported and to close the circuit between the said uprights and the terminals A' , the eccentric blade b^2 is operated 110 in the same manner as described, but in a reverse direction—that is, the springs $b^{10} b^{12}$ are first expanded and the bar c engaged with the end wall 5 of the slot c' to partially remove the blade b^2 from its terminals of the set A^2 and then completely removed therefrom substantially in an instant by the 115 springs $b^{10} b^{12}$, after which all the blades are moved past the center, and the blade b^2 is moved longitudinally to engage the slot c^2 with the bar c , and the recesses b^{17} are brought into engagement with the rods $b^{13} b^{14}$. 120

With the construction herein shown the eccentric blade b^2 is positively closed on both sides of the double-throw switch and is spring-actuated in opening with the same or substantially the same spring force on both sides 125 of the switch—that is, when the blade b^2 is in engagement with the coöperating terminals a^3 of the set A' its removal therefrom is completed by the force of the expanded springs $b^{10} b^{12}$, and when in contact with like 130 terminals of the set A^2 the spring force employed in removing the said blade from the terminal a^3 of the set A^2 is the same or substantially the same. Furthermore, the blade

b^2 is positively engaged with its terminals a^3 of the sets $A^1 A^2$ by means of the cross-bar c , which in one instance engages the end wall 2 of the slot c^2 and in the other instance engages the end wall 4 of the slot c' . As a result a double-throw quick-break switch is obtained in which the movable member is positively moved into its closed position on both sides of the center and is opened by a yielding medium which disengages said blade from its terminals with the same quickness or rapidity on either side of the center.

I prefer the construction herein shown, in which the eccentric blade is interposed between two concentric blades, which have the function of a carrier for the eccentric blade; but I do not desire to limit my invention to the particular construction shown. So, also, this invention may be embodied in a quick-break switch having but a single throw and is further adapted to be embodied in a multipole switch by increasing the number of the blades b^2 to correspond to the poles of the multipole switch. When embodied in a multipole switch, the carrier for the movable members need not coöperate with spring-fingers of the stationary terminals.

I may prefer to effect the positive connection between the movable member and its carrier as herein shown—that is, by providing the movable member with slots and the carrier with a projection or bar to engage said slots; but I do not desire to limit my invention in this respect, as this construction may be reversed—that is, the slots may be formed in the carrier and the projection or bar attached to the movable member.

I claim—

1. In an electric switch or circuit-controller, the combination of the following instrumentalities, viz: stationary members located on opposite sides of a center, and a movable member coöperating with said stationary

members and comprising an eccentrically-mounted blade provided with curved slots of substantially the same radius but having different centers, a carrier for said eccentric blade, a cross-bar attached to said carrier and extended through one of said slots and adapted by movement of the eccentric blade to register with the other of said slots, and means to yieldingly connect the eccentric blade with its carrier, substantially as and for the purpose specified.

2. In an electric switch, a movable member comprising an eccentrically-mounted blade movable in an arc of substantially one hundred and eighty degrees, and provided with communicating slots of substantially the same arc but of different centers, a bar or rod extended into one of said slots and adapted to register with the other of said slots by longitudinal movement of the eccentric blade, means to actuate the said bar independent of the eccentric blade, and a yielding medium engaging said eccentric blade and actuated by the means which move the said bar, substantially as described.

3. In an electric switch, the combination with an eccentrically-mounted movable member, of a pivoted actuating-carrier, means to connect said movable member with the actuating-carrier comprising connected curved slots of substantially the same radius but having different centers in one member, and a bar or projection rigidly attached to the other member, and a yielding medium actuated by the independent movement of the carrier, for the purpose specified.

In testimony whereof I have signed my name to this specification in the presence of two subscribing witnesses.

JOHAN M. ANDERSEN.
